(Cl. D58—8)

To all whom it may concern:

Be it known that we, Donald J. Schwarz and Melvin E. St. Clair, citizens of the United States, residing respectively at 4425 Mayhew Road, Cincinnati, Ohio, and 272B South Marshall Street, Hartford, Connecticut, have invented a new, original, and ornamental Design for a Combined Plastic Bottle and Cap Therefor, of which the following is a specification, reference being had to the accompanying drawing, forming a part hereof.

Fig. 1 is a front elevation of a combined plastic bottle and cap therefor embodying our new design;

Fig. 2 is a side elevational view thereof, with the cap portion being shown in cross section;

Fig. 3 is a top plan view thereof; and
Fig. 4 is a bottom plan view thereof.

We claim:

The ornamental design for a combined plastic bottle and cap therefor, as shown.

DONALD J. SCHWARZ.
MELVIN E. ST. CLAIR.
